UNITED STATES PATENT OFFICE

92,021

DESIGN FOR A LADY'S VANITY CASE

Colette Sachs, Paris, France, assignor to Elizabeth Arden Sales Corporation, New York, N. Y.

Application January 26, 1933, Serial No. 46,993
In France October 10, 1932

Term of patent 7 years

To all whom it may concern:

Be it known that I, COLETTE SACHS, a citizen of the French Republic, residing at Paris, France, 5 Rue Villaret de Joyeuse, have invented a new, original, and ornamental Design for Lady's Vanity-case, of which the following is a specification, reference being had to the accompanying drawing, forming part thereof.

In the drawing:

Figure 3 is a view similar to that in Figure 2 but relates to the opening of the other compartment of the vanity-case.

What I claim is:

The ornamental design for a lady's vanity-case, substantially as shown.

Signed at Paris, France this 10th day of January 1933.

COLETTE SACHS.
